UNITED STATES PATENT OFFICE.

CALEB E. SUMMERS, OF DAYTON, OHIO, ASSIGNOR TO GENERAL MOTORS RESEARCH CORPORATION, OF DAYTON, OHIO, A CORPORATION OF DELAWARE.

INDICATOR.

Application filed December 20, 1922. Serial No. 607,963.

This invention relates to lubricating systems of automobiles and has among its objects the provision of a signalling device for indicating the lack of lubricant in the 5 lubricating system.

Further objects and advantages of the present invention will be apparent from the following description, reference being had to the accompanying drawing, wherein preferred forms of embodiments of the present 10 invention are clearly shown.

In the drawing;

Fig. 1 is a fragmentary side view of an engine partly in section to which the present 15 invention is applied.

Fig. 2 is a wiring diagram showing the circuit connections for providing a visible signal and

Fig. 3 is a fragmentary sectional view 20 showing a modified form of the invention.

The internal combustion engine 20 to which the present invention is applied is provided with a lubricating system which includes a duct 21 through which lubricating 25 oil flows into a vessel 22 of non-conducting material. During the normal operation of the lubricating system, the lubricant will fill the box 22 and will flow over the upper edge thereof into a pan 23 which forms the lower 30 part of the crankcase. As shown in the pending application of Kettering and Short, Serial No. 553,938, filed April 17, 1922, this pan includes a plurality of troughs each for collecting oil to be splashed by a connecting 35 rod of the engine in the usual manner of splash oil systems. There being lubricant in the vessel 22 the cork float ball 24 will rise to the position shown in Fig. 1 and will draw after it a metallic contact 25 connected with 40 the float ball by means of a rod 26. Rod 26 is smaller in diameter than the hole in the bottom of the box 22 but not so small as to prevent filling the box 22 with lubricant during the normal operation of the lubricating 45 system. This contact 25 will engage two electrical contacts 27 and 28 supported by the bottom of box 22. The contact 28 is grounded at 29, the contact 27 is connected by wire 30 with a switch contact 31 adapted to be connected by movable switch contact 50 with a contact 33. Contact 33 is connected by wire 34 with a lamp 35 which in turn is connected by wire 36 of the battery 37.

The switch contact 32 is actuated by pull 55 button 40. To render the signalling device operative, the pull button 40 is pulled to the left to cause the contact 32 to engage the switch contacts 31 and 33. As long as a sufficient amount of lubricating oil is flowing 60 out of the pipe 21 the float 24 will be maintained in elevated position causing the contacts 27 and 28 to be engaged by contact 25. Current will flow then from the battery 37 to the light 35, to indicate that 65 the lubricating system is operative. If it is undesirable to burn the light continually the switch button 40 may be pushed in. The burning of the light when the button 40 is pulled out will indicate that the lubricating 70 system is operative.

A baffle 41 is attached to the box adjacent 75 the outlet end of pipe 21 to prevent lubricating oil being thrown directly onto the float ball 24 to interfere with its operation.

When the lubricating system is operating properly the box 22 will be filled to overflowing, the excess spilling over the sides of the box and leaking past the contact 25. If the flow of lubricant through pipe 21 should substantially cease, the box 22 will be emptied on account of leakage past contact 25. If this leakage be not rapid enough then a small hole 22^a can be provided in the box 22 near the bottom. The box 22 would 80 be emptied if the flow through pipe 21 is less than through hole 22^a. The size of this hole can be determined according to the factor of safety of the lubricating system.

If the light should fail to burn this will 85 indicate that the box 22 is not being properly filled with oil and that the splash troughs connected with the pan 23 are not receiving sufficient lubricant.

The system can be arranged so that the light will burn only when the lubricating 90 system is inoperative, that is, the box 22 is not being filled with lubricant. Referring to Fig. 3 the bottom of the box is provided with a conical seat 50 to receive a conical portion 51 of a float member 52. This conical portion is provided with a band 53 of conducting material adapted to engage contacts 54 and 55 connected respectively with wires 30 and 29 of the system shown in Fig. 2. When the box 22 is empty the float 52 will rest upon the bottom of the box with the band 53 in engagement with the contacts 100 105

54 and 55. When this occurs, provided the switch 40 is pulled out, current will flow from the battery to cause the lamp to burn. The float 52 is provided with a rod 26 which cooperates with a hole 57 in the bottom of box 22 to serve as a guide for the float.

Obviously an audible signal could be substituted for the electric lamp 35, such a signal being an electric bell.

While the forms of mechanisms herein shown and described constitute preferred forms of embodiment of the present invention it is to be understood that other forms 15 might be adopted, all coming within the scope of the claims which follow.

What I claim is as follows:

1. In a device of the class described, a vessel and means for supplying a liquid 20 thereto, said vessel having a hole in its bottom wall; a switch; a float located within said vessel and having a rod depending through the hole aforesaid; and means whereby said float may act to close a circuit 25 controlled by said switch, said vessel having a second unobstructed hole adjacent its lower end and through which liquid may flow therefrom.

2. In a device of the class described, a vessel and means for supplying a liquid 30 thereto, said vessel having a hole in its bottom wall; two insulated terminals carried by said vessel; a float located within said vessel and having a rod depending through the hole aforesaid; and a circuit 35 closing member carried by said float and adapted to close a circuit in which said terminals are included, said vessel having a second unobstructed hole adjacent its lower 40 end and through which liquid may flow therefrom.

3. In a device of the class described, a vessel, and means for supplying a liquid thereto, said vessel having a hole in its bottom wall; two terminals carried by said 45 bottom wall; a float located within said vessel and having a rod depending through the hole aforesaid; and a circuit closing member carried by said float and adapted to close a circuit in which said terminals are 50 included, said vessel having a second unobstructed hole adjacent its lower end and through which liquid may flow therefrom.

In testimony whereof I hereto affix my signature.

CALEB E. SUMMERS.
